Grosfillex Contract, p. 27, Lounge at top right Dec. 1989.

Primary Examiner—Gary D. Watson
Attorney, Agent, or Firm—Dowell & Dowell**[57] CLAIM**The ornamental design for a recliner lounge chair, as shown
and described.**DESCRIPTION**

FIG 1 is a front perspective view of a recliner lounge chair with the back in a raised position showing my new design;
FIG. 2 is a front perspective view showing the backrest lowered to an intermediate position;
FIG. 3 is a front perspective view showing the backrest lowered to a fully reclined position;
FIG. 4 is a front elevational view thereof;
FIG. 5 is a right side view thereof, a view taken from the left
side being a mirror image;
FIG. 6 is a top plan view thereof;
FIG. 7 is a rear elevational view with the backrest in the
raised position of FIG. 1;
FIG. 8 is a rear perspective view thereof showing a storage
compartment housing lid in a raised position;
FIG. 9 is a bottom plan view thereof; and,
FIG. 10 is a perspective view showing the recliner lounge
chair in a folded configuration.
